UNITED STATES PATENT OFFICE.

GARIE H. WILSON, OF CHANUTE, KANSAS, ASSIGNOR OF ONE-HALF TO WILLIAM A. MOON, OF CHANUTE, KANSAS.

TRAIN SAFETY CUT-OUT VALVE.

No. 894,093.

Specification of Letters Patent.

Patented July 21, 1908.

Application filed November 1, 1907. Serial No. 400,194.

To all whom it may concern:

Be it known that I, GARIE H. WILSON, a citizen of the United States, residing at Chanute, in the county of Neosho and State of Kansas, have invented new and useful Improvements in Train Safety Cut-Out Valves, of which the following is a specification.

On locomotives as constructed today it is usual to place under the brake valve in the train line air pipe a cut out valve, the same being placed there for the purpose of cutting the air out of the engineer's brake valve when two or more engines are coupled to one train. When such valve is closed there is no communication to the train line from the brake valve. In double-header service it often happens that the engineer on the second engine will open this cut out valve and pump air into the train line to help the forward engine to obtain the maximum pressure. This practice is all right if done while the train is standing and would not be dangerous if the engineer were infallible, but after cutting the air into the train line to help the forward engine it frequently happens that the engineer forgets to cut off the air and cut out the brake valve of his engine. It is impossible for the engineer on the leading engine of a double-header train to handle a train of air brakes when the cut out valve on the second engine is open, allowing air to flow from the main reservoir into the train line. With the valve of this invention it is impossible for the second engine to pump air into the train line when the safety valve has been adjusted to its cutting off position.

The object of this invention is to overcome the difficulty above noted and insure perfect control of the brakes by one engine without interference on the part of a second or helper engine.

With the above and other objects in view, the nature of which will more fully appear as the description proceeds, the invention consists in the novel construction, combination and arrangement of parts hereinfter fully described, illustrated and claimed.

In the accompanying drawings, Figure 1 is a sectional view of the valve showing the first or initial position. Fig. 2 is a similar view showing the second position of the valve. Fig. 3 is a similar view showing the third position of the valve.

The valve comprises essentially a valve casing A which is cylindrical and has con-

nected thereto at three different points as shown, the rear train line air pipe 1, the forward train line pipe 2 and the train line pipe 3 to the brake valve, the pipes 1 and 3 being directly opposite each other, while the pipe 2 is located half way between the pipes 1 and 3. The valve casing is also provided with a port 4 to which the air gage pipe is connected and is also provided with another port 5 for the escape of air as a signal to the engineer. 60 65

The valve B is rotatably mounted in the valve casing A and contains the three main passages 6, 7 and 8, the passages 6 and 7 being in diametrical alinement with each other and the passage 8 communicating centrally 70 with the combined passages 6 and 7, and disposed perpendicularly thereto. The valve is also provided with a small exhaust passage 9 and another small port or passage 10 which is adapted to be brought into alinement with the port 4 of the valve casing so as to direct the air to the air gage; the passages 9 and 10 are disposed obliquely with reference to the passages 6 and 7 with which they communicate as clearly shown in the drawings. The 75 valve B is also provided with a peripheral recess or port 11 adapted to direct the air through the vent 5 for a purpose which will hereinafter appear.

C designates a handle connected with the 85 valve B for turning the latter to either of the positions illustrated in the drawings.

The normal position of this safety cut out valve is shown in Fig. 1 with the handle C standing upright in which position the valve 90 gives direct communication to the rear train line air pipe 1 from the brake valve pipe 3, all the remaining ports being closed.

The double-header position for this cut out valve is illustrated in Fig. 2 wherein the handle C has been given a quarter turn or brought to a horizontal position, the valve in this position cutting out the brake valve of the second engine or the engine by which said cut out valve is carried and giving a direct 100 train line communication from the forward train line pipe 2 to the rear train line pipe 1. This gives the engineer of the leading engine full control of the brakes. In said position also the port 10 registers with the port 4 and 105 supplies the air gage which exhibits the exact train line pressure on the second engine.

The third position of the valve is illustrated in Fig. 3, wherein the handle is shown as given a half turn, extending vertically 110

downward, which position of the valve allows the train line air to flow from the brake valve to both the back and forward train lines 1 and 2.

5 The safety feature of this cut out valve, in case the brake valve becomes inoperative, is obtained when the valve is adjusted to the position shown in Fig. 2, giving direct communication from the train line to the atmosphere through the forward train line, at the same time cutting out the brake line pipe 3 of the second engine.

10 The most important feature of the cut out valve resides in the fact that by giving the valve a quarter turn in case the brake valve becomes inoperative, direct communication is obtained from the train line to the atmosphere. In double heading, the signal or warning port 5 denotes whether the air is 15 working through the valve or not, and is a signal for the second engineer to cut out his brake valve by giving the handle a quarter turn to the position shown in Fig. 2, allowing the train line air to flow from the leading engine 20 through the cut out to the back train line, giving the man on the leading engine control of the brakes while the second engineer is cut out.

25 In double heading service it will be impossible for two engines to pump air into the train line at one and the same time when the cut out valve is carried in the position shown in Fig. 2. Furthermore, the engineer on the second engine can instantly take charge of 30 and handle the train brakes regardless of the leading engine by turning the handle of the cut-out valve to an upright position as shown in Fig. 1. The engineers on both engines have the train line air pressure registered on the 35 air gages in their cabs. In case of a helper engine coupling to the rear of a train, the engineer of the helper engine is notified by the warning port 5 whether or not the air is passing through and is a signal to cut out his 40 brake valve. Also, in double header service, the passage of the air from the forward engine to the train line is controlled by the engineer of the second engine when the air goes through the warning or signal port from the 45 forward engine. The engineer on the second engine will then turn the handle of his valve one quarter giving the forward engine full 50 charge of the brakes. With this valve the engine handling a train of cars can couple 55 into the cars ahead and charge uncharged cars ahead of the engine until the pressure is equalized as indicated by the air gage when the handle of the valve may be moved to the third position shown in Fig. 3. If the for-

ward engine becomes uncoupled the engineer 60 on the second engine can instantly take charge of the brakes and have the maximum air pressure restored and have the train ready to move when the forward engine is re-coupled. Furthermore, it is impossible to 65 blow the dirt from the train line into the working parts of the brake valve when the leading engine is coupled.

Having thus fully described the invention, 70 what is claimed as new is:—

1. A safety cut out valve for air brakes comprising a valve casing having diametrically opposite ports communicating with the rear train line air pipe and the brake valve air pipe, and a port intermediate thereof 75 communicating with the forward train line pipe, and a rotatable valve mounted in said valve casing and comprising three ports or 80 passages two of which are in diametrical alinement with each other and the third running perpendicular thereto, substantially as described.

2. A safety cut out valve for air brakes comprising a valve casing having diametrically opposite ports communicating with the rear train line air pipe and the brake valve air pipe, an intermediate port communicating with the forward train line air pipe, and an air gage port, and a valve rotatably 85 mounted in said casing and comprising a diametrical passage or port leading therethrough, another port extending perpendicularly to said diametrical port, and an air gage 90 controlling the port leading from the diametrical port outward through the valve and adapted to register with the air gage port of 95 the valve casing.

3. A safety cut out valve for air brakes embodying a valve casing having diametrical opposite points communicating with the rear train line air pipe and the brake valve pipe and an intermediate port communicating with the forward train line pipe and located midway between the two first named ports and further provided with a warning or signal port, and a valve rotatably mounted in 100 said casing and comprising a diametrical passage, another passage communicating therewith and extending perpendicularly thereto, and a peripheral recess adapted to communicate with the warning or signal port, substantially as and for the purpose described.

105 In testimony whereof I affix my signature in presence of two witnesses.

GARIE H. WILSON.
